METHOD OF MAKING MULTIPLY TRAYS

Joseph A. Potchen, Grand Rapids, Mich., assignor to Haskelite Manufacturing Corporation, a corporation of New York

Application December 5, 1938, Serial No. 243,924

3 Claims. (Cl. 154—2)

Decorative panels both flat and in the form of trays or the like, are commonly composed of plywood, the facing plies of which are usually veneers of the rarer, more expensive woods. The object 5 of the present invention is to produce a satisfactory product of this kind which shall cost very much less than the usual plywood devices.

In carrying out my invention, I substitute for the usual face veneers, sheets of fibrous material, 10 usually paper. Therefore, viewed in one of its aspects, the present invention may be said to have for its object to produce a simple and novel multiply panel having decorative or ornamental facings of paper or the like.

15 In order to reduce the cost of manufacture of multiply trays, it is desirable that the bonding of the core and face members be carried out simultaneously with the molding of the parts into the desired shapes. When the bonding and the molding is effected by pressing an assembly of plies between dies, some parts of the paper for the upper or inner side of the tray are under compression while other parts are in tension. While the proper kinds of paper stretch sufficiently to prevent rupture of the paper during molding, paper does not compress readily and, therefore, wrinkles form in areas, such as those at the corners of a cornered tray, where the need for compression is considerable.

20 A further object of the present invention is to make it possible to manufacture a tray faced with paper or other fibrous material without creating wrinkles in the facings.

In carrying out the last-mentioned object of 25 my invention, I so shape the mold or die faces in the areas where the paper is subjected to the greatest amount of compression with ridges or ribs so disposed that, instead of compressing, the paper may take a more or less sinuous shape that 30 eliminates wrinkling and adds to the ornamental appearance of the tray.

The various features of novelty whereby my invention is characterized will hereinafter be pointed out with particularity in the claims; but, 35 for a full understanding of my invention and of its objects and advantages, reference may be had to the following detailed description taken in connection with the accompanying drawing, wherein:

Figure 1 is a top plan view of a tray embodying 40 the present invention; Fig. 2 is a view similar to Fig. 1, on a much larger scale, and showing only a corner of the tray; Fig. 3 is a section on line 3—3 of Fig. 2, but on a larger scale; Fig. 4 is a section on line 4—4 of Fig. 2; Fig. 5 is a perspective 45 view of a fragment of one of the facing sheets

ready to be applied to a core for the making of a panel; Fig. 6 is a more or less diagrammatic view showing a pair of cooperating die members, two facing sheets and a core member adapted to form an assembly for a tray, all separated from each other, but arranged in the order in which they appear at the beginning of a bonding and molding operation; Fig. 7 is a bottom view of one-half of the upper die member shown in Fig. 6; Fig. 8 is a top view of one-half of the lower die member 5 of Fig. 6; and Fig. 9 is a section on a greatly enlarged scale on line 9—9 of Fig. 7.

In the drawing I have illustrated my invention as applied to a tray, and the method of manufacturing the same, and the detailed description 15 will be confined to this particular embodiment, since it will be evident that flat panels can be produced in the same way, except that no molding is required and flat pressure plates or platens may be employed instead of dies to effect the bonding.

The tray is composed of three separate layers, 20 namely a core layer 1, an upper facing layer 2, and an under facing layer 3. The layer 1 may be a piece of wood veneer or a piece of thin, inexpensive plywood, whereas the layers 2 and 3 are 25 sheets of paper. It is my purpose that the tray shall be complete, except for edge trimming, upon the bonding together and the molding of the three layers, so that no subsequent finishing operations are needed to place a tray in condition 30 for use. When the core member is to be composed of a plurality of plies, these plies may be bonded together as a preliminary step, or the bonding thereof may occur simultaneously with the bonding of the core to the facing members. Therefore,

35 as a preliminary step, I decorate the surface of each facing sheet that is exposed when the tray has been made, if decoration is desired, and coat that surface with a lacquer; both pigments and lacquer being chosen for their ability not to fade or disintegrate at subsequent curing temperatures of from 200° F. to 300° F. Thus, I am enabled to apply the decorations and the lacquers by a rolling process. By a similar process, the opposite side 40 of the paper is coated with an adhesive material, preferably of the artificial resin type. In this way the decorative and protective coatings for the tray and the glue coatings to effect the bonds between the layers and the tray are not only applied 45 rapidly, but uniformity of distribution of the coating materials and avoidance of an accessible amount of such materials results.

After the coatings on the paper, including the glue coatings, have become dry, two paper facings 50

and a core member are assembled and the bonding and molding operation is carried out.

In Fig. 5 there is shown one of the facing sheets having on one surface or side the finishing coat 4 and on the other side a glue coating 5. In making the assembly of the several layers, the glue coatings of the facing sheets are, of course, laid against the faces of the core member 1. The assembly is then placed between male and female dies, 6 and 7 respectively, which provide a die cavity which corresponds to the shape of the tray to be produced. The dies are closed so as to exert the necessary pressure on the assembly for the tray to mold the latter into tray form, and the dies are heated in any suitable way, not shown, to cure the glue.

The tray illustrated is substantially rectangular and has sloping side walls which meet at the four corners of the tray. The paper of the upper facing sheet 2 is placed under compression in the corners of the tray and, because the paper does not compress easily, its manner of yielding to the compressive stresses is to form wrinkles. In order to avoid wrinkles, I flatten the corners of the tray so that contiguous side walls do not quite meet each other, but are separated by a flat strip or band 8 extending from the bottom of the tray to the top. The female member of the die has flattened corner sections 9 and the male die member has flattened corners 10; the flattened portions 8 of the panel being formed between the complementary die faces 9 and 10.

It is not sufficient to make the corners flat, but room must still be provided to accommodate the excess paper stock which would otherwise develop wrinkles in these areas. I have found that if the faces 10 of the male die member are provided with shallow ribs 11 extending parallel with each other from points near the bottom of the tray to the top, so as to produce a corrugated effect on the paper, the excess paper stock which would otherwise create wrinkles is taken up in these corrugations, indicated at 12, so that not only are wrinkles avoided, but decorative ridges 45 are developed in the corners of the tray without undue stretching of the paper.

By properly choosing the facings of paper or other fibrous materials, and the pigments and lacquers, as well as the adhesives, a panel containing an inexpensive core may be manufactured at a cost which is only a small fraction of the cost of a similar panel composed entirely of plywood and, at the same time, my panel will be as attractive and serviceable as the other. A great 55 advantage is attained in the manufacture of trays because of the fact that a tray is complete, except for edge trimming, upon leaving the molds or dies, and the further fact that the pigments, lacquers and glues can all be applied to the paper facing material by means of rollers, whereby a minimum amount of material is used and the cost of application of the materials to the facings is insignificant. It will also be seen that my

improved method of controlling the action of the paper in areas of compression so as to produce ornamental designs in lieu of wrinkles, not only enhances the appearance of the trays, but avoids the considerable loss that would otherwise occur because of wrinkling to such an extent as to make it unnecessary to discard a substantial percentage of trays.

I claim:

1. The method of making a multiply tray having a bottom and sides inclined thereto, said sides meeting in corners, which comprises coating flexible fibrous sheet material with an adhesive substance, permitting the adhesive to dry, assembling two pieces of such coated fibrous material with their adhesive-coated faces toward each other and a flat core member interposed between the same, pressing the assembly together and molding it into the desired shape under conditions to bond the whole together, and during the molding operation, corrugating the fibrous material in the corners on the inner side of the tray from the bottom to the rim in directions to offset the tendency to wrinkle under molding forces that place the said sheet material under compression in the tray corners.

2. The method of making a multiply tray having a bottom and sides inclined thereto, said sides meeting in corners, which comprises coating one face of a flexible fibrous sheet material with a finishing layer of lacquer and the other face with an adhesive substance that requires heat and pressure to set the same, permitting the lacquer and the adhesive to dry, assembling two pieces of such coated fibrous material with their adhesive-coated faces toward each other and a flat core member interposed between the same, pressing and heating the assembly to bond the plies together and mold the panel into the desired shape, and during the molding, corrugating the paper in the corners on the inner side of the tray from the bottom to the rim where the fibrous material is under compression.

3. The method of making a multiply tray having a bottom and sides inclined thereto, said sides meeting in corners, which comprises coating one face of a flexible fibrous sheet material with a finishing layer of lacquer and the other face with an adhesive substance that requires heat and pressure to set the same, permitting the lacquer and the adhesive to dry, assembling two pieces of such coated fibrous material with their adhesive-coated faces toward each other and a thin, flat, wood core member interposed between the same, pressing and heating the assembly to bond the plies together and mold the panel into the desired shape, and during the molding, compressing the wood on the inner side of the tray at the corners to produce corrugations extending from the bottom of the tray to the rim and compelling the inner or top layer of fibrous sheet material to follow the contours of such corrugations.

JOSEPH A. POTCHEN.
